UNITED STATES PATENT OFFICE

2,493,616

PORTABLE TABLET DISPENSING UNIT

Alexander Burns, New York, N. Y.

Application October 30, 1946, Serial No. 706,631

1 Claim. (Cl. 206—42)

1

This invention relates to a container for medicinal tablets and more particularly to a device of the type that is adapted to be carried on the person of an individual.

The principal objective of my invention was to design such a container that could be used for the carrying and dispensing of tablets of various shapes and sizes. The use of my device obviates the necessity of a person touching the tablets with his hands which, of itself, can be harmful to a certain extent when the hands are moist or unclean.

Another advantage of my device is that it is sturdily constructed of unbreakable material that will afford the tablets the maximum amount of protection from breakage and moisture. Also, there will be no danger of the container breaking which would be a possibility if it came in contact with a hard object while in a purse being carried by an individual or while in a pocket of the wearer's apparel.

A further feature of my device provides for the dispensing of a tablet while the remaining tablets in the container remain completely covered.

Another feature of my device provides a locking unit that prevents operation of the dispenser when the supply of tablets has been exhausted and at the same time provision is made in the form of an additional tube in order that a reserve supply of tablets may be carried.

Today with the large portion of the people taking vitamin pills, my device offers a convenient and compact method for carrying these tablets on the person.

Further advantages and unique features of my device will be apparent as I proceed with the description.

Referring to the drawings:

Figure 1 shows a cross section view on line 1—1 of Figure 2.

Figure 2 shows an end elevation.

Figure 3 shows a plan elevation.

Figure 4 shows a bottom view.

Figure 1 illustrates a cross section view of my tablet dispensing unit 10 which is composed of a body portion 11 and a sliding cover 18. Formed out of the body 11 are two circular tubes 12 and 13. Tube 13 is shorter in length than tube 12 and carries a reserve supply of tablets 28. Tube 13 is closed at one end with the opposite end being equipped with a threaded cap 15 which is screwed into the body 11.

The dispensing tube 12 is somewhat larger than the reserve tube 13 and consequently holds a larger supply of tablets. The bottom end of the

2

dispensing tube 12 is also sealed by a threaded cap 14 while the dispensing end of this tube opens into a pocket 19 in the sliding cover 18.

Attached to the inner side of cap 14 is a feed spring 16 which furnishes the necessary force to move the tablets 28 toward the upper or dispensing end of the tube 12. Attached to the upper portion of the spring 16 is a plug 17 which is circular in form and slightly smaller in diameter than the tube 12 and performs several functions. It furnishes a smooth, protective surface on which the tablets 28 rest and also fills up the pocket 19 in the cover 18 when the last tablet has been dispensed and in this manner acts as a locking device in that under such circumstances it prevents any movement of the sliding cover 18.

The sliding cover 18 is equipped with a pocket 19 which is positioned directly above the dispensing tube 12 when the cover is in its normal or closed position. The pocket 19 will be approximately the same size or slightly larger than the tablets being used as it is contemplated to manufacture this device in various sizes to handle tablets of varying sizes and shapes.

25 The opposite end of the cover 18 has a downward extended portion 29 which is substantially semi-circular in shape and which portion covers the groove 22 in which is positioned a return spring 21. The function of the spring 21 is to 30 return the cover to its normal position after a tablet has been dispensed. Securing the cover 18 to the body portion 11, are two pins 20 and 23 which terminate in reduced areas 24 and 25 respectively that are anchored in the body portion 11. The pins 20 and 23 extend up and through slots 26 and 27 which are near the edges of the cover 18 and extend along the long sides of the cover which is rectangular in shape.

The heads of the pins 20 and 23 are larger 40 in diameter than the width of the slots 26 and 27 and the movement of the cover is guided and controlled by these pins. When the cover is moved to dispense a tablet, the extent of its movement is controlled by the end of the slots which contact the pins and also the spring 21 which is compressed when the cover is operated.

To prepare the unit 10 for operation, both tubes 12 and 13 are filled with tablets 28 and the caps 14 and 15 are screwed into place. The spring 16 will force a tablet 28 into the pocket 19 and the unit is ready to dispense tablets. By sliding the cover 18 toward the dispensing tube 12, the pocket 19 will be exposed and the tablet will fall into the user's hand or glass as desired.

When the finger pressure has been released from the sliding cover, the spring 21 which has been compressed by movement of the cover 18, will return the cover back to its original position. This will enable the spring 16 to force another tablet into the pocket 19 and the unit is prepared for another operation. When the supply of tablets has been exhausted in tube 12, the plug 17 will be forced in the pocket 19. As the plug 17 is of a greater height than the tablets, it will not only fill up the pocket but a portion will also remain in the tube 12 preventing the movement of the cover 18.

When this locking device takes effect, it will indicate to the operator that the supply of tablets has been exhausted and must be replenished from the reserve in tube 13.

In its preferred form, it is contemplated to manufacture this unit utilizing plastic, however, metal or other suitable materials may be used.

Whereas I have described my invention in its preferred form, it is realized that minor changes may be made without departing from the principal scope of the invention.

I claim:

A tablet dispensing device of the type described including a body portion and a sliding cover, said cover attached to the body through pins which have one end anchored in the body and opposite ends extending through guide slots in the cover, two elongated holes formed in said body to pro-

vide a storage tube and a dispensing tube, said storage tube being sealed at one end and being equipped at the opposite end with a threaded cap, said dispensing tube having an open dispensing end adapted to be closed by the sliding cover, the cover being equipped with a pocket positioned directly above the dispensing tube, opposite end of the dispensing tube being equipped with a threaded cap, spring means positioned in said dispensing tube, said means including a spring which is attached at one end to the threaded cap and the opposite end being attached to a plug on which the tablets are placed, said spring means being adapted to force a tablet into said pocket in the cover, said cover capable of being slidably operated to expose said pocket and thereby to dispense the tablet, said cover being equipped with spring means to return the cover to closed position after the said dispensing operation.
